UNITED STATES PATENT OFFICE.

LEWIS MILLER, OF AKRON, OHIO.

GRAIN-BINDING HARVESTER.

SPECIFICATION forming part of Letters Patent No. 331,808, dated December 8, 1885.

Application filed May 6, 1884. Serial No. 130,556. (No model.)

To all whom it may concern:

Be it known that I, LEWIS MILLER, of Akron, county of Summit, and State of Ohio, have invented a new and useful Improvement 5 in Grain-Binding Harvesters, of which the following is a full, clear, and exact description, reference being had to the accompanying drawings, making part of this specification.

The invention relates to a novel construction of the rear sill of the platform-frame, whereby it is made to form a part of the inclined binder-frame; to the manner of combining the binder-frame and its supports with the platform-frame, and to the construction of 10 the standard bracket or chair supporting the upper side of the inclined binder-frame, whereby it is made also to serve as a tongue-socket, and is provided with a sleeve-bearing for the secondary or pinion shaft, through which it is 15 connected with the drive-wheel arm or frame; to the manner of combining the axle block or sleeve and the curved standard on the adjustable platform-frame with the secondary or pinion shaft having its bearings in a standard 20 bracket or chair on the platform-frame, by means of an arm connecting the pinion and drive-wheel axle-block, and serving to hold 25 said parts always in proper working relation to the pinion-shaft; and to the manner of bracing 30 the rear portion of the platform and binder frames for properly supporting the same, and for leaving an open space under the binder-table in rear of the binding devices, for facilitating access to the latter for repairs or other 35 purposes, all as hereinafter explained.

In the accompanying drawings, Figure 1 is a plan view of a harvesting-machine with the binder-table removed and parts of the binder-gear standard and mechanism broken away or 40 removed to show the arrangement of the platform-frame, binder-frame, and main drive-wheel. Fig. 2 is a side elevation with the drive-wheel broken away in part to show the arrangement of the curved guiding-standard, 45 the axle block or sleeve in which said standard is adjustable, and the arm connecting said axle-block with the pinion-shaft. Fig. 3 is a front elevation of the grain-wheel end of the machine, and Fig. 4 is a rear elevation showing 50 the form of the rear platform and binder-frame sill.

A represents the forward sill or finger-bar, and A' the rear sill of the platform-frame, made preferably of metal and in the form of angle-iron plates, each with its wider portion 55 upright and with the horizontal portion or flanges at its lower edge turned inward in such manner as to form supporting-ledges, on which the lower flooring for protecting the platform-carrier is supported. These may be united at 60 their outer or grain end by a similar iron, or in any usual or preferred way, and form light, substantial, and convenient sills for the attachment of other parts of the platform-frame and carrier. The rear sill, near its inner end, is 65 bent upward or has an upwardly-inclined extension-piece, A², secured to it, which in the present construction is made to serve also as the rear transverse sill of the inclined binder-frame, which, aside from said rear sill, is composed of longitudinal bars or tubular rods B B', 70 inclined transverse bars C C' C'', connecting said longitudinal rods at points intermediate of their ends, and a curved bar, C³, at their forward ends, as shown. The upper longitudinal 75 bar, B', is supported at its rear end in the upper end of the inclined extension A² of the rear platform-sill, and at its forward end in a standard bracket or chair, D, secured to the forward sill, A, near its inner end, and the lower 80 bar, B, is similarly supported in the angular extension A², near its lower end, and in a shorter chair or bracket, D', on the forward sill, thereby giving the binder-frame the desired inclination. The standard-bracket 85 D is provided with forwardly-projecting flanges, forming a socket in which the rear end of the tongue is pivoted, with a transverse sleeve bearing or bearings at d for the secondary or pinion shaft a, and with suitable 90 bearings at d' and d'' for the screw and worm-wheel shafts, through which the height of the platform and binder frames is adjusted, by devices similar to those described in Letters Patent No. 276,449, granted to me April 24, 95 1883.

To the stubble end of the sill A is secured the foot of a segmental standard, E, curved in an arc of a circle, of which the pinion-shaft a, mounted in the sleeve-bearings d, is 100 the center, and connected at its upper end by an oblique brace, e, with the standard bracket

or chair D, as shown. The standard E fits and is adapted to slide in a grooved block or sleeve, E', formed on the inner end of axle F, and in one piece with an arm, E², which, at 5 its opposite end has an eye or sleeve, E³, formed upon it, which surrounds the pinion-shaft a, causing the latter, as the platform and binder frames are adjusted, to move up and down in the arc of a circle, of which the 10 main drive-wheel axle F is the center, and holding it in proper working relation to the driving-wheel on said axle, and from which said pinion-shaft receives its motion, while at the same time relieving the curved standard E of 15 much of the backward thrust and strain of the drive-wheel, which would otherwise be thrown upon it.

From the sill A, at or near its inner or 20 stubble end, a truss-rod or brace, g, extends obliquely rearward and upward to the upper end of the angular extension A² of the rear sill, A, and, being rigidly secured thereto or to the longitudinal bar or tubular rod B' near 25 said end, serves to materially stiffen and prevent the sagging of the rear inner corner of the frame. By this arrangement the horizontal lateral extension of the rear sill, as heretofore employed, for supporting the binder-frame is dispensed with, the frame is 30 made lighter at that point, and an open space is provided under the binder-table in rear of the binding devices, making the latter easier of access for repairs or other purpose.

The gathering devices or pickers in this 35 arrangement, relative to the binder-table and to the butting, compressing, and binding devices, are made the subject-matter of a separate application filed herewith, Serial No. 130,557, and the construction of the binder-frame and its supports, aside from the features herein specifically pointed out, are similar to those described in Patent No. 293,345, granted to me February 12, 1884, and need not therefore be here described.

45 Having now described my invention, I claim herein as new—

1. In a grain-binding harvester in which the inclined elevating binder-table is interposed between the platform-carrier and the 50 path of the driving-wheel, the rear platform-frame sill having its inner end bent upward to form the rear transverse bar of the inclined binder-frame, in combination with the longitudinal bars of said binder-frame, supported 55 at their rear ends in said inclined portion of the rear sill, substantially as described.

2. The inclined binder-frame interposed between the platform-carrier and the path of the driving-wheel, in combination with the stand-

ard bracket or chair on the platform-sill, supporting the upper longitudinal binder-frame bar at its forward end, and the upwardly-inclined inner or heel end of the rear platform-frame sill supporting the rear end of said longitudinal binder-frame bar, substantially as 60 described.

3. The combination, with the platform-frame, the inclined binder-frame, and table secured to said platform-frame on the grain side of the driving-wheel, and the interposed 70 binder-frame-standard bracket or chair, of the segmental standard rigidly secured to said platform-frame, the grooved-axle block, within which said standard is adjustable, and an arm pivotally connecting said axle-block with the 75 secondary or pinion shaft mounted in the binder-frame standard or chair, substantially as described.

4. In a grain-binding harvester, the combination of the platform-frame, the binder-frame on the inner end thereof between the platform-carrier and the path of the driving-wheel, a standard-bracket supporting the outer end of the binder-frame above the forward platform sill and provided with bearings for 80 the secondary or pinion shaft, a segmental standard rigidly connected with the platform-frame, an axle block or sleeve within which said standard is adjustable, an arm connecting said axle-block with and adjustable around 85 the pinion-shaft as a center, and means for adjusting the platform-frame, substantially as described.

5. The binder-frame-standard bracket or chair provided with the tongue-socket, and a 95 transverse sleeve-bearing for the secondary or pinion shaft, substantially as described.

6. The binder-frame-standard bracket provided with the tongue-socket, a transverse sleeve bearing for the secondary or pinion 100 shaft, and a bearing for the worm-wheel shaft, through which the adjustment of the height of the frame is effected, substantially as described.

7. The combination of the front and rear sills of the platform-frame, the rear sill having 105 its inner end bent upward to support the rear end of the upper longitudinal binder-frame bar, the chair supporting the forward end of said binder-frame bar, and a brace extending from the inner end of the platform-frame sill 110 in front upward to the angular extension of the rear sill, substantially as described.

In testimony whereof I have hereunto set my hand this 12th day of April, A. D. 1884.

LEWIS MILLER.
